UNITED STATES PATENT OFFICE.

HERBERT H. REINER, OF PHILADELPHIA, PENNSYLVANIA.

SAFETY-GUARD FOR FURNACE-DOORS.

1,101,094

Specification of Letters Patent. Patented June 23, 1914.

Application filed March 13, 1913. Serial No. 753,916.

To all whom it may concern:

Be it known that I, HERBERT H. REINER, a citizen of the United States, residing at Philadelphia, in the county of Philadelphia and State of Pennsylvania, have invented certain new and useful Improvements in Safety-Guards for Furnace-Doors, of which the following is a specification.

My invention relates to improvements in safety guards for furnace doors, the object of the invention being to provide improvements of this character which may be attached to any ordinary double door without altering the latter in the slightest, and which will, in the event of an explosion from within the furnace, prevent doors from being blown open and injuring the firemen.

My improvements are especially adapted for use in connection with steam boiler furnaces where explosions frequently occur in the fire box because of a leaky boiler tube. These explosions blow the doors open and kill or injure the firemen. My improved guard is designed to prevent this blowing open of the doors, yet allow the doors to be readily opened and closed whenever desired.

With these and other objects in view, the invention consists in certain novel features of construction and combinations and arrangements of parts as will be more fully hereinafter described and pointed out in the claim.

In the accompanying drawings: Figure 1 is a view in elevation illustrating my improvements in operative position. Fig. 2 is a view in section on the line 2--2 of Fig. 1, and Figs. 3 and 4 are perspective views of the two members constituting my improved guard.

1 and 2 represent the ordinary doors of a boiler furnace which are provided with integral lugs 3 supported above similar lugs 4 on the door frame 5, and said lugs having aligned openings for the reception of hinge bolts 6. The door 2 overlaps the edge of door 1 when closed, so that it is necessary to first close door 1 and then close door 2. The two members 7 and 8 constituting my improved guard may, of course, be made of various material, but preferably of rod steel

or other strong wire, which at one end is coiled as shown at 9 forming a bearing to receive the hinge bolt 6 and turn freely thereon. This coil 9 has no function of a spring, but merely operates as a bearing. 55 The free end of member 7 is bent upwardly at right angles forming a finger 10, while the free end of member 8 is bent outwardly forming a hook 11. Member 8 is located on the hinge bolt 6 of the outer door 2, and 60 member 7 on the hinge bolt 6 of the inner door 1. These terms inner and outer are used with reference to the overlapping feature of the doors at their juncture.

It will be noted that when in operative 65 position, the hook 11 will engage the finger 10, so that while member 7 may be readily swung out of the way to allow the doors to open, if the doors are blown from inside, due to an explosion, and both doors forced 70 outwardly together, the hook 11 will lock with finger 10 and prevent this movement. In other words, the members 7 and 8 may be readily thrown out of the way by first swinging member 7 whenever it is desired 75 to open the doors, but if at any time an explosion occurs within the fire box, these guards will prevent the doors from being blown open.

Various slight changes might be made in 80 the general form and arrangement of parts described without departing from my invention, and hence I do not limit myself to the precise details set forth, but consider myself at liberty to make such changes and 85 alterations as fairly fall within the spirit and scope of the appended claim.

Having thus described my invention, what I claim as new and desire to secure by Letters Patent is:

The combination with a furnace, hinge bolts on the furnace, two doors mounted on the hinge bolts and adapted to close an opening in the furnace with one door at its free edge overlapping the other door, of a guard 95 comprising two members, said members each consisting of a coil, both rods coiled at one end forming bearings to receive and turn on the hinge bolts, one guard member normally positioned across the outer door 100

and having an outwardly projecting hooked free end, and the other member normally positioned across the inner door and having an upwardly projecting finger at its free end positioned within the hook, substantially as described.

In testimony whereof I have signed my

name to this specification in the presence of two subscribing witnesses.

HERBERT H. REIBER.
